(21) Appl. No.: **29/153,753**

The ornamental design for the male connector for a computer cable, as shown and described.

(22) Filed: **Jan. 9, 2002**

DESCRIPTION

(30) **Foreign Application Priority Data**

Aug. 8, 2001 (JP) 2001-023346

(51) LOC (7) Cl. **13-03**

FIG. 1 is a top view of my new design for a male connector for a computer cable, such as a connector that is mounted on a substrate (board) of a laptop computer and connects to a cable for an LCD display.

(52) U.S. Cl. **D13/147**

FIG. 2 is a front elevation view of the article shown in FIG. 1;

(58) Field of Search **D13/147; 439/62,**

FIG. 3 is a rear elevation view of the article shown in FIG. 1;

439/260, 329, 395, 422, 492, 499, 160,

FIG. 4 is a bottom view of the article shown in FIG. 1;

266, 476.1, 484, 940

FIG. 5 is a right side view of the article shown in FIG. 1, which is a mirror image of the left side view.

(56) **References Cited**

The portion shown in broken lines in FIGS. 2 and 4 are included for the purpose of illustrating portions of the connector that form no part of the claimed design.
